This invention relates to theater chairs and more particularly to chairs of the retracting type which may be moved forwardly or rearwardly in a substantially horizontal plane and which are so mounted that the seat and back may be moved relative to each other.

UNITED STATES PATENT OFFICE

2,492,106

RETRACTING TYPE THEATER CHAIR

Merritt K. Orton, Grand Rapids, Mich., assignor to American Seating Company, Grand Rapids, Mich., a corporation of New Jersey

Application June 29, 1946, Serial No. 680,426

8 Claims. (Cl. 155—116)

1

The present invention relates to chairs and more particularly to chairs of the retracting type for installation in theaters, auditoriums and the like.

The primary objects of the invention are to provide an improved chair of the retracting type wherein the occupant may move the seat rearwardly in order to permit others to pass in front of him without his having to rise from his seat; to provide such a chair which when retracted utilizes a minimum of space to the rear; to provide such a chair having an arrangement of pivoted links for supporting the seat and back and which arrangement provides for easy and comfortable retracting and forwardly returning movements; to provide such a chair whose mountings and operating mechanism are located below the seat level and which are therefore concealed from view; and in general to provide such a retracting chair which is quiet and efficient in operation and attractive in appearance.

Illustrative embodiments of the invention are shown in the accompanying drawings, wherein:

Figure 1 is a perspective view of a retracting theater chair in its forwardly moved position;

Figure 2 is a sectional view thereof taken on line 2—2 of Figure 4 and showing the parts of the chair in their forwardly moved positions;

Figure 3 is a sectional view similar to Figure 2 and showing the parts of the chair in their rearwardly moved positions;

Figure 4 is a fragmentary front elevational view of the mounting and operating mechanism on the right hand side of the chair; and

Figures 5 and 6 are views similar to Figures 2 and 3 showing a slightly modified chair in its forwardly and rearwardly moved positions respectively.

Referring now in detail to Figures 1—4 of these drawings, the retracting chair there shown is mounted upon a frame which comprises spaced upright chair supporting standards 10 secured to the floor in any suitable manner and provided with inwardly extending lugs 11, mounting members 12 having outwardly turned flanges 13, and bolts 14 passing through aligned bolt-receiving apertures in the flanges 13 and in the lugs 11 for securing the mounting members to the standards.

The chair proper generally comprises a seat and back assembly in which the seat 15 and back 16 are pivotally connected for relative movement, and this assembly is so mounted on the standards that when the seat moves rearwardly the back also moves rearwardly and simultaneously turns from its inclined position to a near-vertical posi-

tion. The back 16 is secured to the rearward ends of the standards 10 by means of bolts 17 and nuts 18, the rearward ends of the standards 10 being provided with inwardly turned flanges 19 which are secured to the standards 10 by means of nuts 20 and bolts 21. The back 16 is secured to the flanges 19 by means of bolts 22 and nuts 23.

The seat 15 is secured to the standards 10 by means of bolts 24 and nuts 25, the rearward ends of the standards 10 being provided with outwardly turned flanges 26 which are secured to the standards 10 by means of nuts 27 and bolts 28.

The back 16 is secured to the standards 10 by means of bolts 29 and nuts 30, the rearward ends of the standards 10 being provided with outwardly turned flanges 31 which are secured to the standards 10 by means of nuts 32 and bolts 33.

The back 16 is secured to the standards 10 by means of bolts 34 and nuts 35, the rearward ends of the standards 10 being provided with outwardly turned flanges 36 which are secured to the standards 10 by means of nuts 37 and bolts 38.

The back 16 is secured to the standards 10 by means of bolts 39 and nuts 40, the rearward ends of the standards 10 being provided with outwardly turned flanges 41 which are secured to the standards 10 by means of nuts 42 and bolts 43.

The back 16 is secured to the standards 10 by means of bolts 44 and nuts 45, the rearward ends of the standards 10 being provided with outwardly turned flanges 46 which are secured to the standards 10 by means of nuts 47 and bolts 48.

The back 16 is secured to the standards 10 by means of bolts 49 and nuts 50, the rearward ends of the standards 10 being provided with outwardly turned flanges 51 which are secured to the standards 10 by means of nuts 52 and bolts 53.

The back 16 is secured to the standards 10 by means of bolts 54 and nuts 55, the rearward ends of the standards 10 being provided with outwardly turned flanges 56 which are secured to the standards 10 by means of nuts 57 and bolts 58.

The back 16 is secured to the standards 10 by means of bolts 59 and nuts 60, the rearward ends of the standards 10 being provided with outwardly turned flanges 61 which are secured to the standards 10 by means of nuts 62 and bolts 63.

The back 16 is secured to the standards 10 by means of bolts 64 and nuts 65, the rearward ends of the standards 10 being provided with outwardly turned flanges 66 which are secured to the standards 10 by means of nuts 67 and bolts 68.

The back 16 is secured to the standards 10 by means of bolts 69 and nuts 70, the rearward ends of the standards 10 being provided with outwardly turned flanges 71 which are secured to the standards 10 by means of nuts 72 and bolts 73.

The back 16 is secured to the standards 10 by means of bolts 74 and nuts 75, the rearward ends of the standards 10 being provided with outwardly turned flanges 76 which are secured to the standards 10 by means of nuts 77 and bolts 78.

The back 16 is secured to the standards 10 by means of bolts 79 and nuts 80, the rearward ends of the standards 10 being provided with outwardly turned flanges 81 which are secured to the standards 10 by means of nuts 82 and bolts 83.

Movements of the seat and back when retracted or returned by the chair occupant, are best understood by a comparison of Figures 2 and 3 of the drawings. It will be seen that the seat moves rearwardly and forwardly with the seat carriers in a substantially horizontal path during which movement the back moves rearwardly with the back carriers and assumes a near-vertical position thus to utilize a minimum of space to the rear of the chair. Retracting and forwardly returning movements of the chair are stopped by contact of the rollers 24 with stop means comprising the rearward and forward ends respec-

tively of the races 25. The rear supports 20 are preferably connected by a cross-tie or strut 31 secured thereto as by welding, and the stability of the structure is thereby increased.

The modification of the chair shown in Figures 5 and 6 is the same as the embodiment above described except that the lower ends of the three pairs of front-supporting links 121, 122 and 123 are pivotally mounted on a roller 124 movable in a straight rearwardly-downwardly extending race 125 in the mounting members 112, while the upper ends of the links 123 are pivoted directly to the forward ends of the seat carriers 126, no roller being provided at this latter connection as in the chair shown in Figures 1-4. Forward and rearward movements of this modified chair are substantially the same as the movements of the chair shown in Figures 1-4.

While but two specific embodiments of the invention have been herein shown and described, it will be understood that numerous details may be altered or omitted without departing from the spirit of the invention as the same is defined by the following claims.

I claim:

1. In a chair, a frame, back carriers and a back mounted thereon, rear supports having their lower ends pivotally connected to the frame and their upper ends pivotally connected to the rearward ends of the back carriers, seat carriers having their rearward ends pivotally connected to the back carriers, a seat mounted on the seat carriers, and means for supporting the forward ends of the back carriers and the seat carriers comprising pairs of links, the links of the first pair having their upper ends pivotally connected to the forward ends of the back carriers, and the links of the second pair having their upper ends pivotally connected to the forward ends of the seat carriers and having their lower ends pivotally connected to the lower ends of the first pair, means for mounting one of said pairs of links on the frame for forward and rearward movements relative thereto, and stop means for limiting the forward and rearward movements of said links.

2. In a chair, a frame, back carriers and a back mounted thereon, rear supports having their lower ends pivotally connected to the frame and their upper ends pivotally connected to the rearward ends of the back carriers, seat carriers having their rearward ends pivotally connected to the back carriers, a seat mounted on the seat carriers, and means for supporting the forward ends of the back carriers and the seat carriers comprising pairs of links, the links of the first pair having their upper ends pivotally connected to the forward ends of the back carriers, the links of the second pair having their upper ends pivotally connected to the forward ends of the seat carriers and having their lower ends pivotally connected to the lower ends of the first pair, and the links of the third pair having their rearward ends pivotally connected to the rear supports and having their forward ends pivotally connected to the lower ends of the first and second pairs of links, means for mounting one of said pairs of links on the frame for forward and rearward movements relative thereto, and stop means for limiting the forward and rearward movements of said links.

3. In a chair, a frame having forwardly-rearwardly extending guides at opposite sides thereof, back carriers and a back mounted thereon, rear supports having their lower ends pivotally connected to the frame and their upper ends pivotally

connected to the rearward ends of the back carriers, seat carriers having their rearward ends pivotally connected to the back carriers, a seat mounted on the seat carriers, and means for supporting the forward ends of the back carriers and the seat carriers comprising pairs of links, the links of the first pair having their upper ends pivotally connected to the forward ends of the back carriers, and the links of the second pair having their upper ends pivotally connected to the forward ends of the seat carriers and having their lower ends pivotally connected to the lower ends of the first pair, means movable in said guides associating one of said pairs of links with the frame, and stop means for limiting the forward and rearward movements of said links.

4. In a chair, a frame having forwardly-rearwardly extending guides at opposite sides thereof, back carriers and a back mounted thereon, rear supports having their lower ends pivotally connected to the frame and their upper ends pivotally connected to the rearward ends of the back carriers, seat carriers having their rearward ends pivotally connected to the back carriers, a seat mounted on the seat carriers, and means for supporting the forward ends of the back carriers and the seat carriers comprising pairs of links, the links of the first pair having their upper ends pivotally connected to the forward ends of the back carriers, and the links of the second pair having their upper ends pivotally connected to the forward ends of the seat carriers and having their lower ends pivotally connected to the lower ends of the first pair, rollers turnably mounted on one of said pairs of links and movable forwardly and rearwardly in the guides, and stop means for limiting the forward and rearward movements of said rollers.

5. In a chair, a frame having forwardly-rearwardly extending guides at opposite sides thereof, back carriers and a back mounted thereon, rear supports having their lower ends pivotally connected to the frame and their upper ends pivotally connected to the rearward ends of the back carriers, seat carriers having their rearward ends pivotally connected to the back carriers, a seat mounted on the seat carriers, and means for supporting the forward ends of the back carriers and the seat carriers comprising pairs of links, the links of the first pair having their upper ends pivotally connected to the forward ends of the back carriers, and the links of the second pair having their upper ends pivotally connected to the forward ends of the seat carriers and having their lower ends pivotally connected to the lower ends of the first pair, and the links of the third pair having their rearward ends pivotally connected to the rear supports and having their forward ends pivotally connected to the lower ends of the first and second pairs of links thus forming common pivotal connections between the three pairs of links, means movable in said guides and associated with said links at their common pivotal connections, and stop means for limiting the forward and rearward movements of said links.

6. In a chair, a frame, a seat and back assembly wherein the seat and back are pivotally connected for relative movement, rear supports having their lower ends pivotally connected to the frame and their upper ends pivotally connected to the rearward part of the seat and back assembly, and means for supporting the seat and back assembly in the front comprising links having their upper ends pivotally connected to the seat and the back

respectively and having their lower ends pivotally connected to each other, means for mounting the pivotally connected lower ends of said links on the frame for forward and rearward movements relative thereto, and stop means for limiting the forward and rearward movements of said links.

7. In a chair, a frame, a seat and back assembly wherein the seat and back are pivotally connected for relative movement, rear supports having their lower ends pivotally connected to the frame and their upper ends pivotally connected to the rearward part of the seat and back assembly, and means for supporting the seat and back assembly in the front comprising a set of three links at each side of the chair, the links of each set having a common pivotal connection and being pivotally connected respectively with the seat, the back and a rear support, means for mounting the pivotally connected lower ends of said links on the frame for forward and rearward movements relative thereto, and stop means for limiting the forward and rearward movements of said links.

8. In a chair, a frame having forwardly-rearwardly extending guides at opposite sides thereof, a seat and back assembly wherein the seat and back are pivotally connected for relative movement, rear supports having their lower ends piv-

otally connected to the frame and their upper ends pivotally connected to the rearward part of the seat and back assembly, means for supporting the seat and back assembly in the front comprising a set of three links at each side of the chair, the links of each set having a common pivotal connection and being pivotally connected respectively with the seat, the back and a rear support, rollers mounted at the common pivotal connections of the sets of links and movable forwardly and rearwardly in said guides, and stop means for limiting the forward and rearward movements of said rollers.

MERRITT K. ORTON.
